UNITED STATES PATENT OFFICE.

DIRK EISINGA, OF SEATTLE, WASHINGTON, ASSIGNOR TO AMES SHIP BUILDING AND DRY DOCK COMPANY, OF SEATTLE, WASHINGTON, A CORPORATION OF WASHINGTON.

SCARFING MACHINE.

1,413,712.

Specification of Letters Patent. Patented Apr. 25, 1922.

Application filed April 25, 1918. Serial No. 230,823.

To all whom it may concern:

Be it known that I, DIRK EISINGA, a citizen of the United States, residing at Seattle, in the county of King and State of Washington, have invented a certain new and useful Improvement in Scarfing Machines, of which the following is a specification.

This invention relates to scarfing machines and more particularly to scarfing machines employed in ship building and in other industries where heavy and unwieldy plates or other parts are to be scarfed or beveled.

Heretofore it has been the practice, in scarfing ship plates and the like, to regulate the slope of the scarf by adjusting the plate relatively to the machine, or adjusting the machine as an entirety to the plate. This method of scarfing has been slow and cumbersome owing to the fact that the plates, frequently weighing many tons, are exceedingly difficult to handle, especially when the plates must be accurately positioned to produce a scarf having the desired slope or inclination. Moreover, it is very difficult accurately to reproduce a scarf by this method owing to the difficulty in accurately positioning the plates.

The principal object of the present invention is to provide a scarfing machine adapted to be readily transported and positioned relatively to a plate or other piece of stock to be scarfed so that the stock need not be moved or adjusted in position. Thus the machine may be applied to the stock in whatever position the stock may be supported or at whatever angle the stock may be blocked up.

Other primary objects of the invention are to provide a scarfing machine which may readily be clamped to a plate or other piece of stock, which may be accurately adjusted to cut a scarf of any desired slope, which automatically feeds the cutting tool along the stock, which automatically stops the feeding of the cutting tool when the scarf is completed, which may be fed manually as well as automatically, which affords a quick and ready shift from automatic to manual feed and vice versa, which has improved means for indicating the slope or inclination to which the machine is adjusted such that a skilled mechanic is not required to set the machine, and which by

virtue of its ready adjustment and automatic operation requires little attention.

To the end of attaining the aforesaid objects I provide a machine having attachment means adapted to be attached to the stock and having movable cutting mechanism tiltably mounted on the attachment means. The attachment means is preferably in the form of a bed plate and means, preferably mounted on the bed plate, is provided to clamp or otherwise secure the bed plate relatively to the stock. The cutting mechanism is tiltably mounted on the bed plate through the medium of a tilttable carriage support and a carriage mounted to move in opposite direction, the carriage support being pivotally mounted on the bed plate to rotate about an axis extending transversely along the stock and the carriage being mounted on the support to move in opposite directions longitudinally thereof. The machine as a whole is made portable so that it may be readily applied to a piece of stock and this is preferably accomplished by suspending the machine through the medium of a suitable support attached to the bed plate.

The various ramifications of the invention will be rendered more apparent by reference to the accompanying drawings, in which,—

Figure 1 is a top plan of the preferred embodiment of my improved scarfing machine, parts being broken away;

Figure 2 is a side elevation of the machine, certain parts being shown in vertical longitudinal central section;

Figure 3 is a detail of the tilting mechanism viewed from the side of Fig. 1;

Fig. 4 is a side elevation of the attachment means or bed plate;

Figure 5 is a top plan of the carriage support;

Figure 6 is a side elevation of the carriage;

Figure 7 is a vertical transverse central section of the tool carrier taken on the line 7—7 of Fig. 2;

Figure 8 is a horizontal section of the tool carrier taken on line 8—8 of Fig. 7;

Figure 9 is a horizontal section of the clamping mechanism taken on line 9—9 of Fig. 2;

Figure 9^a is a perspective view of the key-pin shown in Fig. 9;

Figure 10 is a side elevation of the indicating mechanism;

Figure 11 is a top plan of the indicating mechanism, the associated parts of the machine being shown in section;

Figure 12 is a side view of a portion of a ship's hull where three plates come together to form a joint;

Figure 13 is a section on line 13—13 of Fig. 12;

Figure 14 is a perspective view of a plate having one corner scarfed;

Figure 15 is a side view of a joint formed by two hull plates and a longitudinal beam joined together in accordance with the Iserwood system of ship building;

Figure 16 is a section on line 16—16 of Fig. 15; and

Figure 17 is a perspective view of a plate showing a scarf adapted to the Iserwood system of construction.

The embodiment of my invention chosen for the purpose of illustration comprises in general a bed plate 19, a tiltable carriage support 36, a carriage 50, mounted to move in opposite directions, cutting mechanism 105, and a motor 53 for driving the cutting mechanism and for feeding the cutting mechanism along the stock during the cutting operation.

The bed plate 19 comprises a horizontal plate 106 and two arms 20 extending downwardly from the right-hand end thereof and thence under the plate 106 with their upper surfaces in parallelism with the bed plate. The bed plate is provided with a plurality of transverse strengthening ribs as shown in cross section in Fig. 2, and also with a plurality of openings extending vertically therethrough for the purpose of reducing the weight of the plate and for the purpose of permitting certain parts of the mechanism mounted above the bed plate to extend therethrough. Thus I employ the term bed plate to denote a base which is not necessarily a continuous plate but which is preferably substantially flat on its lower surface so that the stock S may be clamped or otherwise held therealong.

My preferred means for clamping the stock against the lower side of the bed plate comprises two pairs of screws 22 and 23 journaled in the horizontal web 21 extending horizontally between the underlying portions of the arms 20. The screws 22 and 23 are provided with integral collars 107 resting in recesses in the upper surfaces of the rib 21 and the threaded upper ends of the screws are provided with nuts 108. Resting on the upper surfaces of the nuts 108 is a platform 24 adapted to bear against the lower side of the stock and clamp the stock against the bottom 106 of bed plate 19. The platform 24 is provided on its lower side with hexagonal recesses fitting over the hex-

agonal nuts 108 to prevent rotation of the nuts when the screws are rotated.

The mechanism for rotating the screws 22 and 23 is illustrated in detail in Fig. 9 and is comprised as follows: A shaft 29 is journaled at its opposite ends in vertical ribs 109 and 110 extending transversely between the arms 20, and surrounding a portion of the shaft 29 is a tubular shaft 27. The shaft 29 is provided with a worm gear 28 meshing on opposite sides with worm wheels fast on the lower ends of the screws 23, and the shaft 27 is provided with a worm gear 26 meshing on opposite sides with worm wheels fast on the lower ends of the screws 22. The shaft 27 terminates at its outer end at the groove 32. A shaft end member 128 fits upon the end portion of the shaft 29, to which said end member is made fast, and extends to the end of the shaft 27. A hand wheel 30 is mounted on shaft 27 and end member 128 so as to slide longitudinally. A cap 33 serves to limit the longitudinal movement of the wheel and keep it upon its mountings. A pin 31 is mounted in the recess in the wheel 30 so as to be pressed inwardly, this pin being wedge-shaped as illustrated in Fig. 9. When the pin extends into both the key-ways 111 and 112, in the shaft 27 and cap 33 respectively, rotation of hand wheel 30 produces rotation of both the shafts 27 and 29, but when the wheel is moved laterally of the groove 32 so that the pin 31 extends only into one of the keyways, one of the shafts may be rotated independently of the other shaft. When the pin extends only into key-way 111 rotation of the wheel 30 produces rotation of the shaft 27 and screws 22 thereby raising or lowering the outer end of platform 24. When key 31 extends only into key-way 112 rotation of the hand wheel produces rotation of the shaft 29 and screws 23 thereby raising or lowering the inner end of the platform 24. Thus by shifting the hand wheel 30 to opposite sides of the groove 32 the inner and outer ends of the platform 24 may be raised or lowered independently, thereby affording means for adjusting the platform 24 to irregular plates.

The carriage support 36 is rectangular in plan outline as shown in Fig. 5 and is provided intermediate its ends with trunnions 35 and 35' adapted to be supported in bearings 34 on the opposite sides of the bed plate 19. In side elevation the carriage support tapers in both directions from the trunnions 35 and 35' as shown in Fig. 2 and extending between the sides of the carriage support are transverse bracing ribs shown in cross section in Fig. 2. As shown in Fig. 7 the carriage support is provided with dovetail guideways 52 on opposite sides thereof to receive guides 52' on the bottom of the tool carriage later to be described.

The mechanism for tilting the carriage support on the bed plate 19 about the trunnions 35 comprises a crank shaft 38 journaled at its opposite ends in bearings 37 in bed plate 19 (Figs. 1 and 4) and extending throughout its central portion through a block 39 slidingly mounted on the bottom of the carriage support, the block 39 being arranged to slide longitudinally of the carriage support on guides 40. The crank shaft 38 is provided at one end with a worm gear 41 keyed thereto and in mesh with this worm wheel is a worm gear 42 mounted on the end of shaft 43 (Figs. 1 and 3). The shaft 43 is journaled in bearings 104 and 114 in the bed plate 19 and is provided on the end opposite to the worm gear 42 with a hand wheel 44 for adjusting the mechanism and with a lock nut 45 for locking the mechanism in adjusted position. Thus by rotating hand wheel 44 the crank shaft 38 is rotated thereby tilting the carriage support 36, the block 39 sliding along the guideway 40 as the crank shaft rotates. When the carriage support has been adjusted to the proper angle the lock nut 45 is tightened to hold the mechanism in this position during the scarifying operation.

The tool carriage 50 has substantially the same plan contour as the carriage support 36 and as shown in Fig. 6 the carriage is provided with a pedestal 113 for supporting the tool carrier.

The tool carrier shown in section in Figs. 7 and 8 comprises a collet 61 extending vertically into the tubular shaft 59 which carries intermediate its length a worm wheel 58 for rotating the tool. Fastened to the upper face of worm wheel 58 by means of screws 58' is a sleeve 63 provided on its outside with a worm 62. In order vertically to adjust the tool mounted on the collet 61 a screw threaded sleeve 76 is provided around the upper end of shaft 59, the worm sleeve 63 abutting against the bearing ring 115 at its lower end and against the nuts 116 secured to the upper end of the shaft 59. Surrounding the sleeve 76 is a sleeve 77 having inner thread meshing with the thread of sleeve 76 and a wheel 79 is provided for rotating the sleeve 77. A flange 78 is provided at the lower end of threaded sleeve 77 to serve as a thrust bearing, a bearing ring 118 being provided between the flange 78 and the flange 117 on the upper end of worm sleeve 63. A lock nut 80 is provided above the hand wheel 79 to lock the hand wheel in adjusted position. By rotating the hand wheel 79 the tool carrier is raised or lowered and by tightening the nut 80 the carrier is locked against vertical movement in adjusted position. Power is transmitted to the gear wheel 58 from motor 53 through the medium of spur gears 54 and 55 (Fig. 1), shaft 56 and worm 57.

For the purpose of automatically moving the tool carriage 50 longitudinally of the carriage support 36 I provide a screw 51 journaled at its opposite ends in the bearings 100 and 101 depending from the carriage 50 (Figs. 2 and 6). The screw 51 extends loosely through lugs 138 extending upwardly from the carriage support (Fig. 5) and threads through a nut 48 disposed between the lugs 138, the nut 48 being prevented from rotating owing to the fact that its lower side is disposed in juxtaposition to the base of the carriage support. Thus when the screw 51 is rotated in bearings 100 and 101 the tool carriage is moved longitudinally of the carriage support as the worm shaft 51 travels through the stationary nut 48 on the carriage support.

In order automatically to feed the tool carriage longitudinally of the carriage support during the scarifying operation—that is, forward (the front being that portion of the machine where the arms 20 are positioned and said forward direction being the only way that the machine is designed to cut)—I connect the screw 51 to the motor 53 and this connection is preferably effected at a point in the transmission system intermediate the motor and the scarifying tool. Thus in Figs. 7 and 8 I have shown a shaft 66 disposed transversely of the shaft 59 and carrying a worm wheel 64 meshing with the worm 62 on sleeve 63. Shaft 66 is geared to a shaft 69 by means of bevel gears 67 and 68 (Fig. 1) and the shaft 69 is geared to the screw 51 by means of bevel gears 70 and 71. Thus the screw 51 is automatically advanced through the nut 48 as the scarifying tool 47 is rotated.

At times it is desirable to move the tool carriage by hand, as for example when rapidly retracting the carriage preparatory to making a new cut, and I therefore provide mechanism for disconnecting the carriage feed from the motor and for reciprocating the carriage by hand. As illustrated in Fig. 8 this mechanism comprises a cone clutch 75 fitting into a conical recess in the back of gear 64, the clutch 75 being formed integrally with a sleeve 120 surrounding the shaft 66 and carrying at its outer end a hand wheel 73. A nut 74 is rotatably mounted on the small end of shaft 66 and is threaded into a recess in the end of hand wheel 73. The nut 74 is prevented from moving longitudinally of the shaft 66 by the nut and washer 126 so that, as it is rotated, it advances or retracts the sleeve 120 along the shaft 66. When the sleeve 120 is advanced into contact with the conical recess in gear wheel 64 the shaft 66 is rigidly connected with the sleeve 65 carrying the gear wheel 64 and inasmuch as the sleeve 120 is keyed to shaft 66 at 121, power may be transmitted from the tool carrier to the

feeding mechanism through gears 62 and 64, clutch 75, sleeve 120, shaft 66, gears 67 and 68, shaft 69, gears 70 and 71. However, when the clutch 75 is disengaged from the gear 64 by nut 74 the feeding mechanism may be operated by rotating the wheel 73, rotation of wheel 73 rotating shaft 66 through the medium of key 121.

In order to indicate the scarfing angle to which the apparatus is adjusted I provide the following mechanism: An arm 81 is fixedly mounted on a pin 122 extending axially from the trunnion 35' and in association with the arm 81 I provide a horizontal scale member 83 and a vertical scale member 84, the scale member 83 being mounted on a bracket 82 and the scale member 84 being adjustably mounted along the scale member 83. The scale member 83 is mounted parallel to the bed plate 19 and perpendicular to the axis of the tiltable support and the scale 84 is disposed perpendicularly to the scale 83 and perpendicularly to the stock. As the tiltable support is rotated on trunnions 35 and 35' the arm 81 moves along the scale member 84. By adjusting the scale member 84 along the scale member 83 to a point displaced from the axis of the trunnions a distance equal to the length of the scarf to be cut and by tilting the support until the arm 81 registers the thickness of the stock on scale 84 the mechanism may be adjusted to cut a scarf of the desired scope or inclination.

In order to adjust the carriage support laterally I provide a screw 86 threaded axially into the trunnion 35 and journaled in a bracket 123, a hand wheel 85 being provided on the outer end of the screw to rotate same. As the screw 86 is rotated the entire carriage support is forced to one side or the other, the trunnions sliding longitudinally in the bearings 34.

A suitable means for suspending the apparatus so that it may readily be applied to a plate or other piece of stock comprises U-shaped members 18 pivotally connected to lugs 124 on the bed plate 19 and connecting at their upper ends with chains 125 or other suitable supporting means.

The operation of the apparatus is as follows: The apparatus is positioned with the plate S disposed as shown in Fig. 2 and the platform 24 is then raised by means of hand wheel 30 until the machine is tightly clamped to the end of the plate. It will be noted that the scarfing operation is confined to a small portion on one corner or at the end of a plate. On account of this and the action of the rotary knives, particularly strong vibratory movements are set up in the plates or stock, which vibratory movements would seriously interfere with the cutting of a smooth scarf if not counteracted. The novel mode of operation of my

machine is specially designed to overcome such interfering vibratory action by being adapted to utilize the weight of the machine itself to hold the plate down firmly and nullify the vibratory tendency. This purpose is also further attained by adapting the clamping means to reinforce and support every portion of the plate subject to the pressure of the rotary knives.

The tiltable carriage is adjusted to the proper angle to cut a scarf of the desired slope by rotating hand wheel 44. The tool carriage is adjusted longitudinally of the carriage support by hand wheel 73 (with clutch 75 disengaged from carrier 64) until the scarfing tool 47 is immediately above the forward edge of the scarf to be cut. The tool carrier is vertically adjusted by hand wheel 79 until the tool 47 is substantially in contact with the stock. By means of hand wheel 85, the carriage guide 36 with all the upper parts is moved transversely until the knives are precisely within the side lines of the scarf to be cut. The clutch 75 is then forced into engagement with gear wheel 64 by means of nut 74 and the motor 53 is started. As the cutting tool rotates the tool is advanced into the stock by the screw 51 and the operation continues until the scarf has been completely cut, the cutting tool having proceeded from the thin to the thick part of the section to be cut away, said thick part being ordinarily equal to the thickness of the plate to be scarfed. The direction of the feed and of the cutting is of the utmost importance because it avoids the necessity of causing the rotary cutter to go through the cutting operation two or more times to cut a single scarf, which is necessary when proceeding in the opposite direction, because in operating in such opposite direction if a section is not first cut off the plate at the end portion buckles, thereby deforming the plate and interfering with the operation of the knives. Also, by causing the rotary knife to move forward in the direction specified by me, I cause the knives to hold the plate in fixed position against the arms 20, thereby preventing longitudinal displacement of said plate or stock and also do I cause said knives to press the stock against the arms 20. Owing to the fact that the opening 46 in the carriage support and the corresponding opening in the bed plate extends entirely to the end of the machine the tool may be advanced beyond the end of the scarf without engaging any part of the machine.

I preferably provide means for automatically stopping the feed when the scarf has been cut and a suitable means for this purpose comprises terminating the screw 51 at a point 72 somewhat short of the end of the shaft. Thus when the threaded portion of the screw 51 has passed beyond the nut 130

48 the carriage feed is automatically rendered ineffective further to advance the carriage.

- 5 In Figs. 12 to 17 I have illustrated certain types of scarfed plates to show the type of scarfing to which my machine is particularly adapted but it will be understood that the machine is not restricted to work of this particular character. In the construction illustrated in Figs. 12 to 13 the scarf 126 is produced at one corner of plate A so that the three plates A, B and C may be joined together as illustrated in Figs. 12 and 13. In Figs. 15, 16 and 17 the scarf 127 is produced intermediate the sides of plate D so that the channel member E may lie flush along one side of the plates D and F when fitted together.

10 20 I claim:

1. A scarfing machine comprising a base which rests throughout its length upon the plate or stock to be cut, forming thereby a stable bearing for said machine as respects 25 said stock to overcome vibration, said base having means for clamping said stock, supporting means adjustably mounted on the attachment means and cutting mechanism adjustably mounted on the supporting 30 means.

2. A scarfing machine comprising a base which rests throughout its length upon the plate or stock to be cut, forming thereby a stable bearing for said machine as respects 35 said stock to overcome vibration, said base having means for clamping said stock, supporting means adjustably mounted on the attachment means for angular adjustment about an axis extending across the stock, 40 and cutting mechanism adjustably mounted on the supporting means.

3. A scarfing machine comprising a bed plate disposed to cause said machine to rest upon the stock to be cut throughout the 45 length of said bed plate, forming thereby a stable bearing for said machine as respects said stock, to overcome vibration, means for clamping the bed plate to the stock and cutting mechanism adjustably mounted on the bed plate.

50 4. A scarfing machine comprising a bed plate disposed to cause said machine to rest upon the stock to be cut throughout the length of said bed plate, forming thereby a stable bearing for said machine as respects 55 said stock, to overcome vibration, means for clamping the bed plate to the stock, and cutting mechanism adjustably mounted on the bed plate for angular adjustment about an axis extending across the stock.

5. A scarfing machine comprising attachment means disposed to bear throughout its length directly upon the upper surface of the stock and also disposed to support the 65 stock on its under side, a carriage support

tiltably mounted on the attachment means and a tool carriage movably mounted on the carriage support, said tool carriage feeding while engaged in the cutting operation in a direction towards the attachment means and 70 a cutting tool mounted on the carriage, said tool serving while cutting to supplementarily fixedly hold the stock against displacement by pressing the same against that part of the attachment means disposed to support 75 the stock on its under side.

6. A scarfing machine comprising attachment means adapted to be secured to the stock, a carriage support having trunnions journaled at opposite sides of the attachment 80 means, and a tool carriage mounted to move in opposite directions on the carriage support.

7. A scarfing machine comprising attachment means adapted to clamp the stock 85 against said means, a carriage support on the attachment means, means for tilting the carriage support about an axis approximately parallel with the stock, and a tool carriage 90 slidable longitudinally of the carriage support.

8. A scarfing machine comprising attachment means adapted to be secured to the stock, a carriage support on the attachment means, means for tilting the carriage support about an axis approximately parallel 95 with the stock, means for adjusting the carriage support longitudinally of said axis, and a tool carriage slidable longitudinally of the carriage support.

9. A scarfing machine comprising attachment means adapted to be secured to the stock, a carriage support tiltably mounted on the attachment means, a tool carriage 105 movably mounted on the carriage support, and a tool carrier adjustably mounted on the tool carriage.

10. A scarfing machine comprising a bed plate, means for securing the bed plate to the stock, a carriage support mounted on the 110 bed plate to rotate about an axis approximately parallel with the stock, a tool carriage mounted on the carriage support to reciprocate longitudinally thereof, and a tool carrier adjustably mounted on the tool carriage to move to and from the stock.

11. A scarfing machine comprising a bed plate adapted to rest upon the upper side of the stock, whereby vibratory movements 115 in the stock are overcome, and one or more arms extending outwardly from one end of the bed plate and thence around the end of the stock and along the other side of the stock to hold the stock against the bed plate.

12. A scarfing machine comprising a bed 120 plate adapted to lie along the upper side of the stock, whereby vibratory movements in the stock are overcome, and one or more arms extending outwardly from one end of the bed plate and thence around the end of 125 the stock to hold the stock against the bed plate.

13. A scarfing machine comprising a bed 130 plate adapted to lie along the upper side of the stock, whereby vibratory movements in the stock are overcome, and one or more arms extending outwardly from one end of the bed plate and thence around the end of

the stock and along the other side of the stock, and means mounted on said arms to clamp the stock against the bed plate.

13. A scarfing machine comprising a bed plate adapted to lie along the upper side of the stock, whereby vibratory movements in the stock are overcome, one or more arms extending from the bed plate around one end of the stock and thence along the opposite side of the stock, and a clamp adjustably mounted on said arms for clamping the stock against the bed plate.

14. A scarfing machine comprising a bed plate adapted to lie along one side of the stock, one or more arms extending from the bed plate around one end of the stock and thence along the opposite side of the stock, and a clamp mounted on said arms for clamping the stock against the bed plate, the clamp being adjustably supported at a plurality of points so that it may be fitted to the stock.

15. A scarfing machine comprising a bed plate adapted to lie along one side of the stock, one or more arms extending from the bed plate around one end of the stock and thence along the opposite side of the stock, a clamp mounted on said arms for clamping the stock against the plate, a plurality of spaced screws for moving the clamp relatively to the stock, a plurality of concentric shafts respectively geared to said screws, and shiftable means for rotating said shafts, said means being adapted to rotate the shafts, either jointly or independently.

16. In a scarfing machine, a bed-plate adapted to rest on the stock and provided with downturned arms extending rearwardly beneath the body of the bed-plate and spaced therefrom to admit the edge of the stock, a tool carriage mounted to move in opposite directions on said bed plate and supported thereon over portions of the bed plate which are adapted to bear on the stock, and means to adjust the angle of carriage-movement in relation to the stock.

17. In a scarfing machine, a bed-plate adapted to rest throughout its length on the stock and provided with downturned arms extended rearwardly beneath the body of the bed-plate and spaced therefrom to admit the edge of the stock, clamping devices mounted on said arms, a tool carriage mounted to move in opposite directions on said bed-plate and supported thereon over portions of the plate which are adapted to bear on the stock, and means to adjust the angle of carriage movement in relation to the stock.

18. A scarfing machine comprising a carriage mounted to move in opposite directions, means for moving the carriage relatively to the stock, a cutting tool mounted on the carriage, said cutting tool advancing at a uniform pitch during the cutting oper-

ation from the thin to the thick part of the section of the stock to be cut away, a motor mounted on the carriage, a transmission means connecting the motor to the cutting tool, and other transmission means connecting the means for moving the carriage to the first transmission means.

19. A scarfing machine comprising a carriage mounted to move in opposite directions, means for moving the carriage relatively to the stock, a cutting tool mounted on the carriage, said cutting tool advancing at a uniform pitch during the cutting operation from the thin to the thick part of the section of the stock to be cut away, means for driving the cutting tool, and means for connecting or disconnecting said means for moving the carriage to or from said driving means.

20. A scarfing machine comprising a carriage mounted to move in opposite directions, means for moving the carriage relatively to the stock, a rotary tool carrier mounted on the carriage, two concentric shafts, one shaft being geared to the rotary tool carrier and the other shaft being geared to the carriage reciprocating means, means to connect and disconnect said shafts to and from each other, and means to rotate the latter shaft when disconnected from the first shaft.

21. A scarfing machine comprising a carriage mounted to move in opposite directions, a rotary tool carrier mounted thereon, said carrier advancing at a uniform pitch during the cutting operation from the thin to the thick part of the section of the stock to be cut away, means for conjointly rotating the tool carrier and moving forwardly the said carriage, and means for automatically stopping the said forward movement of the carriage.

22. A scarfing machine comprising a carriage mounted to move in opposite directions, a rotary tool carrier mounted thereon, said carrier advancing at a uniform pitch during the cutting operation from the thin to the thick part of the section of the stock to be cut away, means for conjointly rotating the tool carrier and moving forwardly the said carriage, and means for automatically stopping the said forward movement of the carriage without stopping the rotation of the tool carrier.

23. A scarfing machine comprising a bed plate adapted to be attached to the stock, a tiltable support mounted on the bed plate, cutting mechanism mounted on the support, and a crank-shaft journaled in the bed plate and engaging the support so as to tilt the support when rotated.

24. A scarfing machine comprising a bed plate adapted to be attached to the stock, a tiltable support mounted on the bed plate, cutting mechanism mounted on the support,

a block mounted on the support to slide lengthwise thereof, and a crank-shaft journaled in the bed plate transversely of the support and connected to said block so as to tilt the support when rotated.

25. A scarfing machine comprising a bed plate disposed to cause said machine to rest upon the stock to be cut throughout the length of said bed plate, forming thereby a stable bearing for said machine as respects said stock to overcome vibration, means for clamping the bed plate to the stock, a carriage guide adjustably mounted upon said bed plate, a carriage movably mounted upon said guide having a cutting mechanism, and means to actuate said cutting mechanism.

26. A scarfing machine comprising a bed plate provided with means at one end thereof fixedly to hold the plate to be scarfed, a carriage guide pivotally mounted upon said bed plate, said guide being adjustable with relation to the plane formed by the surface of the plate or stock to be cut, a carriage movably mounted upon said guide having a cutting mechanism, and means to actuate said cutting mechanism.

27. A scarfing machine comprising a bed plate provided with means at one end thereof fixedly to hold the plate to be scarfed, a carriage guide pivotally mounted upon said bed plate, said guide being adjustable with relation to the plane formed by the surface of the plate or stock to be cut, a carriage slidably mounted upon said guide having a cutting mechanism, means to advance said carriage along said guide so that the cutting mechanism is advanced to the portion of the plate to be cut, and means to actuate said cutting mechanism.

28. A scarfing machine comprising a bed plate provided at one end with hook-like arms, a clamping table supported on said arms so as to hold the plate to be scarfed against the bed plate, a carriage guide pivotally mounted upon said bed plate, said guide being angularly adjustable relative to the plane of the plate and said guide having mechanism to indicate the angle of the guide to the plate, a carriage slidably mounted upon said guide having a cutting mechanism, means to advance said carriage along said guide, means to operate said cutting mechanism and to move said carriage along said guide, so that the cutting mechanism is advanced automatically to the portion of said plate to be cut.

29. A scarfing machine comprising a bed

plate provided at one end with hook-like arms, a clamping table supported on said arms so as to hold the plate to be scarfed 60 against the bed plate, a carriage guide pivotally mounted upon said bed plate, said guide being angularly adjustable relative to the plane of said plate and said guide having mechanism to indicate the angle of the 65 guide to the plate, a carriage slidably mounted upon said guide having a cutting mechanism, means to advance said carriage along said guide, means to operate said cutting mechanism and to move said carriage 70 along said guide so that the cutting mechanism is advanced automatically to the portion of said plate to be cut, and means automatically to stop the advance of the carriage when the cutting of the scarf is completed.

30. In a scarfing machine, a tiltable tool support, in combination with means for indicating the slope of the scarf comprising an arm mounted to tilt with the tool support, a scale member disposed adjacent said arm in parallelism with the stock and perpendicular to the axis of the tiltable support, and a scale member disposed adjacent said arm perpendicular to said first scale 85 member and to said axis.

31. In a scarfing machine, a tiltable tool support, in combination with means for indicating the slope of the scarf comprising an arm mounted to tilt with the tool support, a scale disposed adjacent said arm in parallelism with the stock and perpendicular to the axis of the tiltable support, and a scale member disposed adjacent said arm perpendicular to said first scale member and 90 to said axis, the scales being arranged respectively to indicate the length and thickness of the scarf.

32. In a scarfing machine, a tiltable tool support, in combination with means for indicating the slope of the scarf comprising an arm mounted to tilt with the tool support, a scale member disposed adjacent said arm in parallelism with the stock and perpendicular to the axis of the tiltable support, and a scale member disposed adjacent said arm perpendicular to said first scale member and to said axis, the second scale member being adjustably mounted on the first scale member.

In witness whereof, I hereunto subscribe my name this 20th day of April, A. D. 1918.

DIRK EISINGA.
